(57) CLAIM

The ornamental design for a media player case, as shown and described.

DESCRIPTION

FIG. 1 shows a perspective view of a design for a media player case.

FIG. 2 shows a perspective view of the design with an open cover.

FIG. 3 shows a front view of the design with a closed cover.

FIG. 4 shows a front view of the design with an open cover.

FIG. 5 shows a rear view of the design.

FIG. 6 shows a rear perspective view of the design.

FIG. 7 shows a right side view of the design; and,

FIG. 8 shows a left side view of the design.

The broken-line features in the figures are for illustrative purposes only and form no part of the claimed design.
